Patented Mar. 23, 1915.

UNITED STATES PATENT OFFICE.

CARL G. HALL, OF PITTSBURGH, PENNSYLVANIA.

COMBINATION COLLAR-BOX.

1,132,578.

Specification of Letters Patent. Patented Mar. 23, 1915.

Application filed November 25, 1913. Serial No. 802,985.

To all whom it may concern:

Be it known that I, CARL G. HALL, a citizen of the United States, residing at Pittsburgh, in the county of Allegheny, State of Pennsylvania, have invented certain new and useful Improvements in Combination Collar-Boxes; and I do hereby declare the following to be a full, clear, and exact description of the invention, such as will enable others skilled in the art to which it appertains to make and use the same.

This invention relates to new and useful improvements in toilet articles and is directed particularly to the provision of a collar and cuff box.

The object of the present invention resides in the provision of a collar and cuff box which is especially adapted for use by travelers and with which is associated means for holding neckties, whereby the same may be carried without their becoming creased from folding, and a further object of the invention resides in the provision of such a device which is simple and compact in structure and which may be easily operated.

With these and other objects in view, the invention resides in the novel combination, formation and arrangement of parts to be more fully hereinafter described and illustrated in the accompanying drawings and particularly pointed out in the claim hereto appended.

Reference is had to the accompanying drawings wherein similar characters of reference designate corresponding parts throughout the several views, and in which:

Figure 1 is a side elevational view of the improved box, Fig. 2 is a longitudinal sectional view taken centrally therethrough, Fig. 3 is a sectional view showing the attachment of one of the clamps, and Fig. 4 is a perspective view of one of the spring clips.

Referring now more particularly to the accompanying drawings, 5 designates the base of the improved collar and cuff box to which is secured the annular side walls 6, the wall being of less diameter than the base, so that the base projects outwardly of

the wall to form a flange 7. An inner annular wall 6' is provided, concentric with the outer wall to thus form two compartments in the body of the box. The upper edge of the wall 6 is provided with an outwardly extending flange 8 for a purpose 55 hereinafter apparent.

The cover comprises a plate 9 carrying an annular flange 10 adapted to seat within the wall 6 and frictionally engage the same. On the top face of the cover is provided a small box 11 having a hinged cover 12, which serves as a jewel or trinket box and which possesses the added function of providing a grip or handle member for the cover. To the base 5 of the box is pivoted a ring 13.

Means are provided for clamping neckties to the outer peripheral surface of the wall 6 which comprises spring clips detachably secured to the flanges 7 and 8. Each of these clips comprises a length of spring wire bent in substantially U-shaped form and having its arms 14 curved through the major portions of their length and directed outwardly at their free end portions at 15 and terminating in eyes 16. The flanges 7 and 8 carry adjacent their periphery inwardly extending pins 17 which are positioned in the eyes of the clip members and said flange and cover plate also carry adjacent the wall 6 pins 18 which engage the arms of the U-clips at the juncture of their lateral portions 15 and hold said arms against the wall 6, the bight portions 19 of the U-clips being thus held resiliently against the wall 6 to clamp the neckties thereagainst. It is observed that the clips may be very readily attached or detached, by swinging the arms thereof inwardly.

From the foregoing it is observed that a simple device has been provided which will 90 efficiently perform all of the functions normally required thereof.

What is claimed is:

A device of the class described comprising a receptacle, spaced flanges extending outwardly from the wall thereof, clamping members each comprising a U-shaped length of spring material, eyes at the free end of

the arms of said length, alined pins carried by the flanges for detachably securing the eyes of each length and pins carried by the flanges and engaging the arms to hold the 5 bight portion of each length in clamping engagement with the said wall of the receptacle.

Copies of this patent may be obtained for five cents each, by addressing the "Commissioner of Patents, Washington, D. C."

In testimony whereof, I affix my signature, in the presence of two witnesses.

CARL G. HALL.
